UNITED STATES PATENT OFFICE.

WILLIAM M. DWYER, OF CHICAGO, ILLINOIS, ASSIGNOR TO WILLIAM H. MINER, OF CHAZY, NEW YORK.

BLUE-PRINT-WASHING MACHINE.

1,290,134.

Specification of Letters Patent.

Patented Jan. 7, 1919.

Application filed June 9, 1917. Serial No. 173,866.

To all whom it may concern:

Be it known that I, WILLIAM M. DWYER, a citizen of the United States, residing at Chicago, in the county of Cook and State of Illinois, have invented a certain new and useful Improvement in Blue-Print-Washing Machines, of which the following is a full, clear, concise, and exact description, reference being had to the accompanying drawings, forming a part of this specification.

This invention relates to improvements in blue print washing machines.

In the washing and fixing of blue prints, considerable difficulty has heretofore been experienced in properly uniformly washing the blue prints and properly uniformly applying the potash solution and furthermore, painful injuries have sometimes been occasioned to the operators due to contact with the potash solution while handling the wet blue prints.

The object of my invention is to provide a blue print washing machine of simple construction and so arranged as to promote uniform washing of the entire sheet and uniform application of the "fixing" solution and without the necessity of the operator touching the paper after it is wet.

In the drawing forming a part of this specification, Figure 1 is a side elevation of a machine embodying my improvements. Fig. 2 is an end elevation of the machine illustrated in Fig. 1. Fig. 3 is a vertical transverse section of the upper portion of the machine illustrated in Fig. 1, and taken on the line 3-3 thereof. Fig. 4 is a detail view of one of the water spraying pipes. Fig. 5 is a broken view similar to Fig. 2 illustrating another embodiment of the invention. And Fig. 6 is a sectional view similar to Fig. 3 illustrating a still further embodiment of the invention.

Referring first to the construction illustrated in Figs. 1, 2 and 3, the machine is shown as comprising sheet metal ends 10-10 tapered in their upper portion as indicated at 11-11, said ends being mounted on suitable angle-irons 12-12 at the bottom, the latter being adapted to rest upon the floor.

The ends 10-10 are maintained in their proper spaced relation by means of longitudinally extending bars 13-13 at the bottom, the bars 13 being also oscillatable in suitable

bearings 14, and a pair of longitudinally extending water spray pipes 15-15 near the top thereof. Mounted between the ends 10 of the machine, near the top is a clamping table having a central ridge 16 and oppositely downwardly inclined surfaces 17-17. To the lower edges of each of the inclined portions 17 is attached the upper edge of a metal sheet 18 which is downwardly curved at a steeper inclination, as clearly appears from Fig. 3, each of the sheets 18 terminating along a line indicated at 19. Below the line 19, another sheet 20 is extended downwardly in the same plane as the corresponding upper sheet 18, the sheets 20 terminating at their lower edges, as indicated at 21, in a large trough 22, the latter having a drain pipe 23 leading therefrom, as clearly indicated in Figs. 1 and 2.

Coöperable with the inclined table portions 17, are longitudinally extending clamping plates 24-24 mounted on the ends of a pair of wings 25 pivotally mounted about a central longitudinally extending axis 26. In Fig. 3, two blue print sheets 27-27 are shown in clamped position between the clamping plates 24 and the respective inclined beds 17. It will also be noted that the water spray pipes 15 have the spray holes 28 thereof so positioned as to direct a plurality of fine streams of water 29 on to the uppermost exposed portion of the blue print sheets.

To operate the clamps 24, each of the rods 13 at the bottom of the machine is provided with a plurality of levers 30 having a foot treadle 31 secured thereto at their outer ends. Also connected to each of the rods 13, on the outside of the ends of the machine, are inwardly extending levers 32, each of which is pivotally connected to an adjustably connecting rod 33. The rods 33 are pivotally connected at their upper ends, as indicated at 34, to the ends of the respective clamping plates 24, the latter having brackets 35 from which extend short studs 36 engaging in eyes at the upper ends of the links 33. In this connection, the ends of the machine are suitably slotted as indicated at 37, to accommodate the movements of the brackets 35. Each of the connecting rods 33 extends through a bracket 38 near the bottom of the machine and against which bears one end of a spring 39, the opposite

end of the spring 39 being held by a pin or other suitable device 40 on the connecting rod.

With the arrangement above described, it is apparent that the springs 39 will act against the rods 33 to hold the clamping plates 24 normally down. When it is desired to insert the edge of a blue print in the clamp, the operator depresses the proper foot-treadle 31, thus opening the clamp and after inserting the edge of the blue print, removal of the foot from the treadle will cause the clamp to return to closed position and thus grip the blue print. The flow of water on the blue prints is controlled by valves 41-41.

For the convenience of the operator, a receptacle 142 for the potash solution may be detachably supported on one edge of the trough 22, as clearly illustrated in Figs. 1 and 2.

As will be understood, the blue prints are placed in the machine while dry and after the same have been thoroughly washed, it is then necessary to apply the "fixing" solution of potash which the operator can readily do by means of a brush, and in this connection it will be understood that a firm backing for the entire blue print is provided by the sheets 18 and 20, thus insuring a uniform application of the fixing solution.

After the blue print has again been washed, it is necessary that the same be removed from the machine and without the operator coming in contact with the chemicals employed. To accomplish this result, a pair of inclined guide-ways 42-42 are formed, down which a plurality of rods 43-43 are adapted to gravitate, said rods 43 being inserted through suitable openings 44 in the end walls of the machine. At the bottom of each of the gravity run-ways 42, a shoulder 45 is provided, which catches the lowermost rod therein. When the blue print is to be removed from the machine, the operator grips the lowermost rod 43 in back of the blue print and pulls the blue print outwardly by said rod, thus folding the blue print partly over the rod. With the blue print thus caught on the rod, the corresponding clamp 24 is released by depressing the treadle 31 and the blue print thus removed from the machine without the operator coming into contact therewith. The rods 43 will be made of a length slightly less than the distance between the ends 10 of the machine but longer than the blue print and access to the ends of the rods is permitted by cutting away the sheets 18 at the places indicated at 46 in Fig. 1. In order to maintain the supply of rods 43, the operator will place the same in the machine through the openings 44 as fast as the same are taken from dry prints.

With the arrangement shown in Figs. 1,

2 and 3, the machine can be operated from both sides simultaneously, thus obtaining a maximum capacity, or one side can be operated at a time, if desired.

In the construction illustrated in Fig. 5, the arrangement is quite similar to that illustrated in Figs. 1, 2 and 3, except that a single water spray pipe 114 is employed instead of two of such pipes. Said spray pipe 114 is mounted on a swinging arm 50 which is pivoted about an axis 51 at the top of the machine. The lever 50 is adapted to be swung back and forth by means of an operating handle 52 which is pivotally attached to a bracket 53 that in turn is secured to the upper pipe 51. Adjustable stops 54 are provided on the end of the machine against which the handle 52 rests in the operating positions of the spray pipe 114. The arrangement of clamps and foot treadles for operating the same is similar to those in Figs. 1, 2 and 3. In operating the machine illustrated in Fig. 5, when a blue print is finished, the operator swings the spray pipe to the opposite side and then releases the blue print and takes it out of the machine by means of a rod, as heretofore described.

In the construction illustrated in Fig. 6, the spray pipe 214 is mounted at the lower end of a swinging lever pipe 250 that in turn is secured at its upper end to an oscillatable pipe 251 mounted in suitable bearings supported on the machine. In this construction, only one blue print 227 at a time can be washed, the same being held by a clamp 224 pivotally mounted on a longitudinally extending rod 226, the clamp 224 being held down under normal conditions by means of suitable spring 39. From the clamp 224 extends an off-set lever 61 which is adapted to be engaged by the spray pipe 214 as the latter is swung rearwardly. The dotted lines in Fig. 6 indicate the manner of releasing the clamp 224 by swinging the spray pipe 214. The pipe 214 is swung by means of a suitable foot-treadle which actuates a connecting rod 233 that in turn is pivoted to a lever 62 clamped to the pipe 251. In this arrangement, the rods are fed down a chute 242 which has its intake mouth 63 at the upper end thereof on the rear side of the machine.

I claim:

1. In a machine of the character described, the combination with an inclined wall on which a blue print is adapted to be supported, and clamping means to hold the upper edge of the blue print, of means for spraying the blue print while the latter is in clamped position, and a run-way in back of the position occupied by the blue print in which a rod may be supported and withdrawn to fold the blue print thereover.
2. In a machine of the character de-

scribed, the combination with an inclined wall on which a blue print is adapted to be supported, and clamping means to hold the upper edge of the blue print, of means for spraying the blue print while the latter is in clamped position, and an inclined run-way opening into said wall and down which rods are adapted to gravitate, said run-way having a shoulder near the bottom thereof to

10 stop the lowermost rod.

3. In a machine of the character described, the combination with an inclined wall on which a blue print is adapted to be supported, and clamping means to hold the upper edge of the blue print, of means for spraying the blue print while the latter is in clamped position, and an inclined run-way opening into said wall and down which rods are adapted to gravitate, said run-way having a shoulder near the bottom thereof to

20 stop the lowermost rod, and foot-controlled means for operating said clamp.

4. In a machine of the character described, the combination with an upper stationary clamping surface, an inclined wall extending downwardly therefrom, and a pivoted clamp coöperating with said clamping surface, means for spraying a blue print while held by the clamping means, and means for temporarily supporting a rod in the rear of the position occupied by the blue print while being washed, the rod being readily withdrawable to thereby fold the blue print thereover.

35 5. In a machine of the character described, the combination with oppositely arranged clamping surfaces and inclined walls extending therefrom, of pivotally mounted clamping plates coöperatively associated

with said surfaces, means for directing 40 streams of water against the upper portions of blue prints held in the clamping means, and duplicate means for temporarily supporting rods in the rear of blue prints held in the machine, said rods being readily withdrawable outwardly to thereby fold the blue prints thereover.

6. In a machine of the character described, the combination with oppositely arranged clamping surfaces and inclined walls 50 extending therefrom, of pivotally mounted clamping plates coöperatively associated with said surfaces, means for directing streams of water against the upper portions of blue prints held in the clamping means, 55 and duplicate means for temporarily supporting rods in the rear of blue prints held in the machine, said rods being readily withdrawable outwardly to thereby fold the blue prints thereover, said clamping plates being 60 independently operable by a foot-treadle.

7. In a machine of the character described, the combination with an inclined wall adapted to form a backing for a blue print or the like while being sprayed, of 65 means for holding the upper edge of a blue print, means for spraying the blue print while held in position on said wall, said wall being provided with an opening therein at a point normally in back of a blue print 70 while being held, said opening being adapted to permit a rod to be withdrawn therefrom outwardly to fold the blue print thereover as the rod is withdrawn.

In witness that I claim the foregoing I 75 have hereunto subscribed my name this 20th day of May, 1917.

WILLIAM M. DWYER.
